US0D1074930S

(12) **United States Design Patent** (10) **Patent No.:** **US D1,074,930 S**
Coppes et al. (45) **Date of Patent:** **** May 13, 2025**

(54) **MANIFOLD FOR FLUID SYSTEM MANAGEMENT**

(71) Applicant: **Advanced Drainage Systems, Inc.**, Hilliard, OH (US)

(72) Inventors: **Bryan Coppes**, Old Saybrook, CT (US); **Alexander Shain**, Lyme, CT (US)

(73) Assignee: **Advanced Drainage Systems, Inc.**, Hilliard, OH (US)

(**) Term: **15 Years**

(21) Appl. No.: **29/868,621**

(22) Filed: **Dec. 8, 2022**

(51) LOC (15) Cl. **23-01**

(52) U.S. Cl.

USPC **D23/233**

(58) **Field of Classification Search**

(57) **CLAIM**

The ornamental design for a manifold for fluid system management, as shown and described.

DESCRIPTION

FIG. 1 is a top right front perspective view for a manifold for fluid system management, showing the new design;

FIG. 2 is a top left rear perspective thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a side view thereof, and the opposite side view is a mirror image thereof.

The broken lines of even length illustrate portions of the manifold for fluid system management and form no part thereof.

1 Claim, 7 Drawing Sheets
